C. Morris,
Sharing Leather,
No 12,444,
Patented Feb. 27, 1855

UNITED STATES PATENT OFFICE.

CHARLES MORRIS, OF NEW HAVEN, CONNECTICUT.

MACHINE FOR SHAVING LEATHER STRAPS.

Specification of Letters Patent No. 12,444, dated February 27, 1855.

To all whom it may concern:

Be it known that I, CHARLES MORRIS, of the city and county of New Haven, in the State of Connecticut, have invented a new and useful Improvement in Machinery for Shaving Straps of Leather for Harnesses, &c.; and I do hereby declare that the following is a full, clear, and exact description of the construction, character, and operation 10 of the same, reference being had to the accompanying drawings, which make a part of this specification, in which—

Figure 1, is a perspective view of the whole machine. Fig. 2, is a view of a cross 15 section of the same, cut vertical through the center; showing the relative position of the operating parts.

My improvement consists in so constructing and arranging the several parts of my 20 machine, that a strap of leather of any thickness used in making harnesses, &c., being drawn through it, with any desired velocity, will have a shaving of any desired thickness, taken off from end to end, and 25 from side to side, leaving the surface of the strap smooth, and even, and ready for blacking, or finishing in any other way, while the strap will remain of essentially the same relative thickness in its several parts as before being shaved; while the machine may 30 be worked by any inexperienced hand.

I make the frame, A, A, A, of cast iron, or any other suitable material, substantially 35 in the form shown in Fig. 1. At the top of this frame I fit a knife, a, Fig. 1, which is also shown in cross section, at a, Fig. 2. And above this knife, a, I fit a gage, B, Figs. 1 and 2. This gage is to govern, or control the thickness of the shaving which is taken 40 from the flesh side of the strap, which may be graduated to any desired thickness by means of the screws, b, b, which serve to hold both the knife and gage to the frame, but as it is designed only to shave the flesh 45 side smooth, suitable for blacking, &c., it will rarely need adjusting. To the lower part of this frame I attach a vibrating frame, C', C', which works on the rod, D, at each end, and the longitudinal bar, C', C', 50 (opposite to the rod, D,) rests upon the two-ends of an elliptic spring E, E, all as shown in Figs. 1 and 2. This spring E, E, is attached to the frame by the stud, d, Fig. 2.

To the central part of the vibrating frame

before described, I fix another vibrating frame, F, which works on the rod, G, at each end, as shown in Figs. 1 and 2, and carries a roller, H, which presses the strap against the edge of the knife, a, by means 60 of the spring, I, I, Fig. 1. This spring is attached to the frame, A, A, A, by the adjusting screw, c, Fig. 2. And I have adjusting screws at each end, as seen at, e, Figs. 1 and 2, (if necessary,) to prevent the 65 roller being brought too near the edge of the knife.

Having made and arranged the several parts, as before described, I pass the two legs, K, K, Fig. 1, into suitable holes in the 70 bench, with the back of the knife toward me, apply my thumb to the thumb piece, L, and force back the roller, as shown in Fig. 1, and insert the end of the strap downward between the roller and edge of the knife, 75 when the spring, I, I, will force the roller forward so as to press the leather against the edge of the knife, when by drawing the strap through, the knife will take off a shaving of the exact thickness of the 80 space between the edge of the knife, a, and the gage, B, while the spring, E, E, will yield so as to allow the roller to conform to the thickness of the strap.

The advantages of my improvement 85 consists in the despatch with which it may be used, as one hand, with the machine, will do more than ten working in the usual way, and will do the work much better:—And any experienced hand can, with the machine, 90 do the work perfectly well, without any danger of injuring the leather, while the most experienced often injure the leather, and even spoil straps, while shaving them in the usual way.

What I claim as my invention, and desire 95 to secure by Letters Patent,

The combination of the knife, (a,) and gage, (B,) with the swinging frame, (F,) when this frame, (F,) is supported by the 100 frame C, C', or its equivalent, to allow this frame, (F,) to yield to the varying thickness of the strap, and the whole is constructed, combined, and made to operate, substantially, as herein described.

CHARLES MORRIS.
